BABY FEEDING DISH

Jacob J. Detzel, Chicago, Ill., assignor to Kay-ware Corporation, Chicago, Ill., a corporation of Illinois

Application October 11, 1951, Serial No. 16,911

Term of patent 14 years

(Cl. D44—15)

To all whom it may concern:

Be it known that I, Jacob J. Detzel, a citizen of the United States, residing at Chicago, in the county of Cook and State of Illinois, have invented a new, original, and ornamental Design for a Baby Feeding Dish, of which the following is a specification, reference being made to the accompanying drawing, forming a part hereof.

In the drawing:

Fig. 1 is a top perspective view of a baby feeding dish embodying my new design;

Fig. 2 is a side elevational view;

Figs. 3 and 4 are sectional views taken respectively along the lines 3—3 and 4—4 of Fig. 1; and

Fig. 5 is a top plan view.

I claim:

The ornamental design for a baby feeding dish, substantially as shown.

JACOB J. DETZEL.
